UNITED STATES PATENT OFFICE.

ZEPHIRIN M. GELINAS, OF YAMACHICHE, QUEBEC, CANADA, ASSIGNOR OF
ONE-THIRD TO OTIS CHAMBERLAIN, OF ENFIELD CENTRE, N. H.

WASHING-MACHINE.

SPECIFICATION forming part of Letters Patent No. 314,372, dated March 24, 1885.

Application filed April 9, 1884. (No model.) Patented in Canada December 18, 1878, No. 9,498.

To all whom it may concern:

Be it known that I, ZEPHIRIN M. GELINAS, a citizen of the United States, residing at Yamachiche, in the county of St. Maurice and Province of Quebec, Canada, have invented a new and useful Washing-Machine, of which the following is a specification, reference being had to the accompanying drawings.

This invention has relation to washing-machines; and it consists in the construction and novel arrangement of parts, as will be herein-after fully described, and particularly pointed out in the claims.

Figure 1 is a view in perspective of a washing-machine embodying my improvements. Fig. 2 is a vertical longitudinal sectional view. Fig. 3 is a transverse vertical sectional view; and Fig. 4 is an end elevation with the bearing-plate removed.

Referring by letter to the accompanying drawings, *a* designates the frame, which has vertical side walls, *b b'*, connected by a top bar, *c*, but in other respects may be of any suitable shape or dimensions. The inner faces 25 of the vertical side walls, *b b'*, are recessed near their middles, and are provided with slotted plates *d d'*, in the slots *d'* of which the studs *e e'*, projecting from the outer faces of the castings *f f'*, which form the bearings for 30 the journals of the wooden plain rollers *g g'*, play vertically when the machine is in operation. The castings *f f'* are connected at their upper ends by the cross-bar *h*, and the bearings for the roller-journals *g g'* open downward and are in the lower edges of said castings, as shown. Tension-springs *i i'* bear upon the upper face of the connecting-bar *h*, and pressure-plates *k k'* rest upon the upper ends 35 of the tension-springs *i i'*, and are operated by screws *l l'* in the top connecting-bar, *c*, to regulate the tension of the rollers to the thickness of the fabric being washed. Below the plain wooden rollers *g g'* is journaled in the vertical side walls of the frame a fluted wooden roller, 40 *m*. One end of this fluted roller has a fixed projecting journal, *n*, while the other end is provided with a rectangular socket, *o*, which receives the rectangular inner end, *p*, of the

short shaft *p'*, carrying a pinion, *q*, and a cog-gear wheel, *q'*. The outer face of the vertical side wall, *b'*, is provided with a metal strip or plate, *r*, which forms one set of bearings for the shafts of the gearing. The other bearings for said shafts (being two in number) are in the removable cover-plate *r'*. A pinion, *s*, 50 having a single bearing in the metal strip *r*, engages the teeth of the pinion *q* on the driving-shaft of the fluted roller *m*. The short shaft *n*, which receives the operating-crank, is provided with a segmental pinion, *w*, and a 55 segmental cog-gear, *x*, the plain peripheral portions being opposed to each other. The crank may be turned in either direction to operate the rollers, and the gearing imparts a 60 rocking motion to the rollers, so that the fabric, which is placed between the fluted roller and the plain roller, will be reciprocated to and fro by the rollers. The teeth on the segmental cog-gear turn the rollers in one direction by engaging the teeth of the cog-gear *q'*, 65 while the teeth of the segmental pinion *w* turns them in the opposite direction when they engage the pinion *q*, so that the fabric is thoroughly rubbed between the rollers, and also moved to and fro in the suds.

Having thus fully described my invention, what I claim as new, and desire to secure by Letters Patent of the United States, is—

1. In a washing-machine, the combination, with the fluted roller having a cog-gear and pinion on the same end of its shaft, of the two plain rollers in bearings regulated by tension-springs, and a crank-shaft provided with a segmental cog-gear and a segmental pinion having their plain arcs opposed, and an intermediate pinion, substantially as specified.

2. In a washing-machine, the combination, with the frame provided with the vertical side walls having slotted guide-plates for the studs on the castings for the plain rollers, the castings connected by the cross-bar and having open bearings in their lower edges, the plain rollers, and the tension-springs regulated by bearing-plates and thumb-screws, of the fluted roller having a socket in one end for its driving-shaft, and full and segmental gearing con-

nected to operate when driven to impart a rocking motion to said rollers, substantially as specified.

3. In a washing-machine, the combination, 5 with the fluted roller and plain rollers, of the removable shaft having the cog-gear q' and pinion q , the pinion s , the crank-shaft with segmental cog-gear x and the segmental pinion w , the bearing-strip r , and the removable cover-plate r' , substantially as specified.

In testimony that I claim the foregoing as my own I have hereto affixed my signature in presence of two witnesses.

ZEPHIRIN M. GELINAS.

Witnesses:

L. A. LORD,
LOUIS PIPETTE.
